Mr. Frederick Grosvenor of Brooklyn, New York, 9770X

Letters Patent.

The schedule referred to in these Letters Patent, and making part of this same containing a description in the words of the said Frederick Grosvenor of his improvement in the manufacture of Palm Leaf hats.

To all to whom these presents shall come, Be it known that I, Frederick Grosvenor of the town of Brooklyn in the county of Kings and the State of New York, have invented a new and useful improvement in the manufacture of Palm Leaf hats, and in certain machinery for preparing and finishing the same, and that the following is a full and exact description of the said improvement.

The inner part of the rim or palm leaf hat; as they have hitherto been made, is flat, or more properly the junction of the crown and rim forms a circle, and the rim itself is perfectly flat; any variation from this shape which are being produced by the stretching when these hats are put on, owing to the oval shape of the head, the front and back part of the rim are forced downward to the annoyance of the wearer, obstructing the view, &c. and the shape of the hat otherwise disfigured, the defect increasing in proportion as the hat is worn and assuming the original shape from which it had been forced by stretching, my improvement is intended to obviate this defect, and consists in bending the hats so as to make the junction of the rim and crown an ellipse instead of a circle, and also to disk or arch the rim on its lower side from front to rear. This is effected by using an oval block and working into the rim by the 8 quadrants of 16 circumference, an additional number of splits proportionable to the extensibility of the ellipse or oval and the required disk which any one acquainted with this kind of work will sufficiently understand to be able to put into practice. The machinery for preparing and finishing consists of several parts as follows.

The first is the machine for preparing the crown, a strong upright timber is turned into a side piece or frame that rests upon the floor, the upright being turned from the side towards the side on which the preparing is performed, through this upright is passed a stationary iron spindle confined by a nut on one side and

and projecting sufficiently far on the other to receive and sustain an iron cog-wheel with a socket at its centre (attached to this wheel) that enters the hat-block; and forms the main bearing; this socket and spindle should enter deep into the block and the diameter of the latter upon which the socket plays freely, should be about 3 inches the better to sustain the pressure. The hat block being secured to the socket by wedges or otherwise, on the face of the cog-wheel is a short lock pin that sustains the block and causes it to revolve with the wheel, also two small arms project horizontally from the same face of the wheel diametrically opposite to each other, to ends of which are secured by thumb screws by which their length are regulated, two hooked slides, which catch the margin of the rim of the hat, the latter being secured by screws into two plates of metal, concurring very nicely to its shape and hold the hat on the block. A small spur wheel immediately above the cog-wheel and which meshes into it, has its bearing or shaft running into a suitable box, on the top of this upright and to this shaft is attached the arm by which the machine is operated, the diameter of the wheel may be varied so as to direct the power and speed. Immediately under the hat-block is the sponge, by which the hat is kept in a proper state of humidity for the operation of pressing; it consists of a metal or wooden slide, to the upper side of which the sponge is attached. This slide rests upon a strip of metal, the end of which under the hat-block has a slot or groove in which works a guide pin or screw fixed in the under side of the slide, the other end of the slide being guided by a pin that passes through a hole in a rectangular arm raised on the stool, the object of this sliding motion being to keep the sponge close to the rim of the hat, whilst revolving to effect which a spiral spring is placed on the guide pin between the arm and slide, also the end of the slide next to the hat rim is bevelled from the under side to support the sponge. 8° and causes it to press on the hat during its revolution. It is connected with the short arm of a weighted lever, immediately under it by a pin that passes through two short bars fixed on the lower side of the stool, this forming at the same time a joint for hinge the lever having its fulcrum in an upright iron rod or bar that passes through the back of the upright, which is moveable up and down, and is made stationary by a thumb-screw, in the side of the brace, by this means the pressure

of the sponge may be regulated, and it will adjust itself to hats of different shapes &c. The iron is a square box the length of which is nearly equal to the height of the crown of the hat, the bottom next to the rim of the hat projecting a short distance, is heated during the operation against one of the plates which encloses the iron and the iron following the inflections or disk of the rim, has a lateral motion that causes it to operate on every part of the crown contiguous to the rim without injury to the latter.

A short arm projects from one side of the box, the end of which is connected by a pin to the top of a post at the side of the machine opposite the block, and a long handle at the opposite side, the arm and handle forming together a lever situated transversely across the block, by bearing on the end of which with the hand or by weight whilst the hat is in revolution, the required degree of pressure of the iron is produced on the iron bolt or heater of which there may be several having been first introduced into the box, also the same post with the iron is heated or attached by a roller or cotton cloth that is placed on the hat before the iron is applied for the purpose of protecting it from the dust &c and removing any extra moisture obtained from the sponge, I prefer the roller upon which the cloth may be wound as it becomes too much soiled for use by which means a clean part of it may be always brought under the iron and much trouble in shifting cloth saved. For preparing the top of the crown, as also the brim, I employ heaters and iron, usually, for the first a circular flat mould with a round depression large enough to admit an ordinary hat, is used, the hat is first put on a solid block or thin smooth plate of metal being first interposed between the iron and block, it is then let upright in the mould heated to a proper degree which the experience of the workman will dictate after which the whole is submitted to a very heavy pressure, by any of the processes now common for a sufficient length of time to produce the desired effect.

The moulds in which the brims are formed, are also of cast iron made very heavy so as to retain the heat — the lower mould is oval and of the shape of which it is designed the iron shall have the upper mould conforms to the lower one exactly except that a large circular opening is left in the middle which admits the crown of the hat to pass through it.

they are also bolted cast with ease or hardly for the convenience of lifting and are likewise supplied with match pins, the hat being placed crown up on the lower mould (which is heated) a thin plate of metal of which there are several to fit hats of different sized crowns and sizes are placed on top of the rim having the same dimensions as the mould, the upper mould also heated is then put on and the whole submitted to a heavy pressure, as before. The lower mould is also used in connection with a cast iron mould, having the same breadth as the rim, to project into proper shape pins made of thick paper which are to be put between the under side of the rim and its lining when the hat is trimmed, for the purpose of stiffening it. Before removing the paper rim from the upper mould its inner edge which projects past the mould for the purpose, is notched or set off, after which a proper shaped block is forced through from the under side which turns up said edge and perfectly adapts the rim to the hat, The paper rims should be broad enough to project past the outer circumference of the hat rim, to be trimmed off when the hat is bound, after which the hats are to be lined and trimmed in the usual manner.

Now what I claim as new and as my invention for which I ask Letters Patent, is the method herein set forth of brading the junction of the rim and crown of the hat oval instead of round, and arched from front to rear, I also claim the heated cast iron moulds used in the manufac- ture herein described, and likewise the machine for ironing the crowns, so far as regards the application of the sponge, and its construc- tion; the cog and spur wheels together with the hooks and plates encircling the rim upon which the hat is held on the block, not meaning to claim hereby the principle of a scotching block which has already been used for similar purposes.

Witness under my hand at this city of Washington this
22 day of May 1836 —

G. Nichols,

Frank Popenoe.
